(57) **CLAIM**

(**) Term: **14 Years**

The ornamental design for a case for portable electronic device, as shown and described.

DESCRIPTION

(21) Appl. No.: **29/243,992**

FIG. 1 is a perspective view of the case for portable electronic device according to the present invention.

(22) Filed: **Dec. 5, 2005**

FIG. 2 is a front view of the case for portable electronic device of FIG. 1.

(51) **LOC (8) Cl.** **03-01**

FIG. 3 is a rear view of the case for portable electronic device of FIG. 1.

(52) **U.S. Cl.** **D3/218**

FIG. 4 is a right side view of the case for portable electronic device of FIG. 1.

(58) **Field of Classification Search** D3/218,
D3/215, 219, 299; 224/666–667, 626, 250,
224/197, 676–681; 379/449, 428

FIG. 5 is a left side view of the case for portable electronic device of FIG. 1.

See application file for complete search history.

FIG. 6 is a top view of the case for portable electronic device of FIG. 1; and,

FIG. 7 is a bottom view of the case for portable electronic device of FIG. 1.
